UNITED STATES PATENT OFFICE.

JAMES M. THOMPSON AND GEORGE P. FRENCH, OF STONEHAM, ASSIGNEES
TO SETH D. TRIPP, OF LYNN, MASSACHUSETTS.

MACHINE FOR POLISHING AND GRINDING THE EDGES OF HEELS FOR BOOTS AND SHOES.

Specification forming part of Letters Patent No. 42,629, dated May 3, 1864.

To all whom it may concern:

Be it known that we, JAMES M. THOMPSON and GEORGE P. FRENCH, residents of Stoneham, in the county of Middlesex and State of Massachusetts, have invented a new and useful or improved machine for polishing or grinding the edges of a heel either of a boot or shoe; and we do hereby declare the same to be fully described in the following specification and represented in the accompanying drawings, of which—

Figure 1 denotes a top view, Fig. 2 a front elevation, and Fig. 3 a side elevation, of our said machine.

Our invention or improvement has reference particularly to mechanism by which the shoe is held and its heel pressed up to and guided, with respect to a rotary grinding or polishing wheel.

In the drawings, A denotes a horizontal shaft suitably supported by a standard, B, and being provided with a driving-pulley, C, a polishing or grinding wheel, D, and a cleaning or buffing wheel E. The wheel D has its grinding-edge formed as seen in Figs. 1, 2, and 3, in order that it may act in the concavity of the periphery of a heel, which, while being ground or polished, is held between and by two rotary clamps, F G, which are supported by and so as to be capable of freely rotating in two carriers or holders, H I, formed as shown in Fig. 2. The longer of these holders—viz., H—is pivoted at bottom within the base of the standard B, and so as to be capable not only of being turned horizontally therein, but of being moved at top in a direction (more or less) toward or away from the wheel D. The other holder, I, is a lever provided with an arm or projection, a, and hinged to an arm, b, extending from the holder H. One of the clamps—viz., that marked G—has its journal c supported by the arm a, as shown in Fig. 4, which is a vertical section of the two clamps and their holders.

The two holders are connected by toggles K K, arranged at the lower end of the holder I, and provided with a lifting-spring, L, which depends from the arm b, and is hooked into one of the said toggles.

The other of the toggles has a rod, d, suspended to it, and extends through a foot-treadle, M, and being provided at its lower end

with a cross-beam or head, e, against which the treadle is to be borne while being pressed downward. By means of the treadle and the said toggles the holder I may be moved in one direction on its fulcrum, so as to move its clamp G away from the clamp F. The spring L operates to close the clamps upon a heel when placed between them, as it will be when the shoe of it is arranged with respect to the holder and clamps, as shown at S in Figs. 2 and 4.

The arm b of the longer holder, H, has a journal, f, projecting upward from it and entering a bearing formed in a slider, g, which is supported by and so as to be capable of sliding horizontally within a frame, N, projecting from the standard B, and carrying another set of toggles, O P, one of which is jointed to the said frame, while the other is jointed to the slider g.

To these latter toggles and their supporting frame a spring, R, is applied for lifting the toggles at their junction, and so as to cause the heel of the shoe held by the clamps to be borne against the periphery of the wheel D. These toggles are connected with the treadle M by means of a rod, g.

When the foot of an attendant of the machine is pressed on the treadle so as to force it downward, the set of toggles O P will be put in operation so as to cause the heel to be ground to be borne away from the wheel D. By still further forcing downward the treadle the other set of toggles will be moved so as to cause one of the clamps to move away from the other, in order to enable the shoe to be removed from the clamps and another substituted in its place.

With our invention the shoe heel is held up to the grinding or polishing wheel by the action of a spring and toggles, and is moved out of action with the wheel by forcing downward the treadle. During the process of grinding or polishing a heel the attendant not only can trim the heel around in a vertical plane, but, by means of the holders, he can move it (more or less) horizontally, so as to cause the grinding-wheel to hollow the edge of the heel or enter and grind in the concavity thereof, as circumstances may require. After the shoe may have been removed from the clamps its heel may be subjected to the action of the buffing or

cleaning wheel E, which is for the purpose of removing from the heel any dirt or dust thereon produced either while grinding or polishing it, such wheel E having its periphery covered with cloth or being provided with a brush or bristles or other proper equivalent.

We claim—

1. The combination of the rotary clamps F G with the turning and vibrating holders H I.
2. The oscillating frame, as composed of the holders H I, the actuating-spring L, and the toggles O P, arranged and combined substantially as specified.
3. The combination of the slider or sliding bearing g, the toggles O P, the spring R, and the treadle M.
4. The combination consisting of the rotary

clamps F G, the turning and vibrating holders H I, the actuating-spring L, the toggles K K, the slider or sliding bearing g, the operating-toggles O P, the spring R, and the treadle M, the whole being arranged, constructed, and applied to a grinding or polishing wheel, D, and so as to co-operate and operate therewith, substantially as specified.

5. The arrangement of the cleansing-wheel E with the grinding-wheel D, and the mechanism, as described, for holding, operating, and grinding the shoe or the heel thereof to be ground.

JAMES M. THOMPSON.
GEO. P. FRENCH.
